UNITED STATES PATENT OFFICE.

JULIUS L. ALLEN, OF WHEATLAND, CALIFORNIA.

FARM-TRACTOR.

1,258,973.

Specification of Letters Patent. Patented Mar. 12, 1918.

Application filed December 22, 1916. Serial No. 138,433.

To all whom it may concern:

Be it known that I, JULIUS L. ALLEN, a citizen of the United States, residing at Wheatland, in the county of Yuba and State 5 of California, have invented new and useful Improvements in Farm-Tractors, of which the following is a specification.

This invention relates to farm tractors, and it has for its object to produce a traction

10 engine of simple and improved construction in which the motor from which power is derived, as well as the means for transmitting motion to the main drive wheel, shall be located entirely within the perimeter of 15 such drive wheel, the latter constituting a cage or housing for such motor and mechanism.

A further object of the invention is to 20 produce a traction engine of the character described having a single drive wheel and motor means for driving the same, thereby dispensing with the use of and necessity for differentials and other complicated and expensive transmission means.

25 A further object of the invention is to produce a simple and improved traction engine of the type described wherein provision is made for utilizing the motor as a stationary engine for driving machinery of 30 various kinds.

With these and other ends in view which will readily appear as the nature of the invention is better understood, the same consists in the improved construction and novel 35 arrangement and combination of parts which will be hereinafter fully described and particularly pointed out in the claims.

In the accompanying drawings has been 40 illustrated a simple and preferred form of the invention, it being, however, understood that no limitation is necessarily made to the precise structural details therein exhibited, but that changes, alterations and modifications within the scope of the claims may be 45 resorted to when desired.

In the drawings,—

Figure 1 is a side elevation of a traction engine constructed in accordance with the invention.

50 Fig. 2 is a top plan view.

Fig. 3 is a transverse sectional view taken on the line 3—3 in Fig. 1.

Fig. 4 is a detail view on a larger scale, partly in plan and partly in section, of the counter shaft and related parts for driving 55 stationary machinery.

Corresponding parts in the several figures are denoted by like characters of reference.

The frame of the machine, which has been 60 shown as being mainly of rectangular form, may be constructed of structural steel, iron, wood or of any desired material or combination of materials, said frame having been shown as including in its construction side 65 members 15, 15', front and rear end members 16, 17 and transversely disposed braces 18, 19 near the front and rear ends, respectively. A seat 20 for the operator is supported at the rear end of the frame. The ground 70 wheel or driving wheel, which is generally designated by B, includes in its construction a hub 21 and a relatively wide rim 22, the hub having flanges 23 that are connected with the rim by spokes 24. The rim is of a 75 width greatly exceeding that of the hub, which latter is positioned with one of its flanges substantially in the plane of one of the side edges of the rim 22, the other flange of the hub being positioned in a plane intermediate the side edges of the rim; the position of the hub may, therefore, be described as being adjacent to one side of the rim. The hub is fixed on an axle 25 which is mounted for rotation in boxes or bearings 26 80 at the upper ends of pedestals or brackets 27 rising from the side members 15, 15' of the frame, which latter will thus be practically suspended from the axle.

Supported within the main frame is an 90 auxiliary frame, generally designated by C, said auxiliary frame having side members, one of which, 26', is firmly connected by means of clips C' with the side member 15 of the main frame. The other side member, 27', 95 of the auxiliary frame has an upwardly extending pedestal or bracket 28 equipped with a box or bearing 29 for the axle 25 from which the auxiliary frame will thus be partly suspended. The auxiliary frame C 100

is located within that portion of the traction wheel B which is not provided with spokes, as is obviously necessary in order to permit rotation of the wheel to take place. The 5 rim 22 of the traction wheel is provided with a circumferential flange 30 of ample width to brace and reinforce that side of the wheel which is not provided with spokes and also to serve as a mud guard for the mechanism supported by the auxiliary frame. The latter is equipped with a platform 31 on which is supported a motor M of the internal combustion or any other suitable and desirable type, said motor having been shown 15 as being equipped with a crank shaft 32 having a fly wheel 33 and a worm 34, the latter meshing with a worm gear 35 on a counter shaft 36, the latter having a pinion 37 meshing with a spur wheel 38 on the axle 25 to 20 which motion will in this manner be transmitted from the source of power. It is obvious that reversing gears, speed gears and clutch means for interrupting the motion when desired are to be provided for, but 25 such devices being well known and in general use, it is not considered necessary to illustrate or particularly describe the same.

The crank shaft 32 has been shown as being provided with a pulley 39 from which 30 motion is transmitted by a belt 40 to a shaft 41 carrying a fan 42 for cooling the radiator 43, it being, however, understood that said radiator may be dispensed with when an air 35 cooled engine is used. The gasoline tank 44 is supported on the platform of the auxiliary frame C.

The side member 15 of the main frame is provided with bearings 45 for a counter shaft 46 which may be driven by means of 40 any well known form of transmission 47 from the crank shaft of the engine. From the counter shaft 46 motion may be transmitted in any convenient manner to stationary machinery of any kind that it may be 45 desired to utilize the motor for driving when the device is not used as a traction engine. It is obvious that in the transmission of power from the counter shaft to the machinery to be driven, suitable clutch means 50 should be included when desired.

The main frame is provided at its forward end with an upwardly and forwardly extending arcuate bracket 48 carrying a swiveled fork 49 which supports the steering wheel 50. The fork 49 carries a worm gear 51 meshing with a worm 52 on a steering rod 53, which latter is partly supported on a bracket 54, said steering rod including a universal joint 55 and a hand wheel 56, 55 which latter is within convenient reach of the operator. The bracket 54 which supports the steering rod rises from the bearing members 26 in which the axle is supported for rotation, said bracket consisting of an 60 inverted yoke that straddles the traction 65

wheel over which the steering rod must obviously be carried.

From the foregoing description taken in connection with the drawings hereto annexed, the operation and advantages of this 70 invention will be readily understood. It will be seen that the traction wheel is made of ample width to enable it to support the frame of the machine without danger of tilting or upsetting. At the same time a 75 traction engine embodying the invention may be constructed of moderate size, enabling it to be operated between rows of growing corn or other plants for the purpose of operating a cultivator or like implement. The improved traction engine is extremely simple in construction, easily handled and steered, and will be found eminently useful for a good many purposes for 80 which more expensive and cumbersome tractors are now generally employed.

Having thus described the invention, what is claimed as new, is:—

1. In a traction engine, a traction wheel comprising a hub, a rim of a width materially exceeding that of the hub and spokes connecting the hub with the rim adjacent to one edge of the latter, an axle fixed in the hub, a main frame having side members, and pedestals rising from the side members and having bearings wherein the axle is supported for rotation.

2. In a traction engine, a traction wheel having a hub and a rim, the latter being of a width materially exceeding that of the hub, 100 an axle fixed in the hub, a main frame suspended from the axle, and an auxiliary frame partly supported on the main frame and partly suspended from the axle, said auxiliary frame being housed within the rim 105 of the wheel.

3. In a traction engine, a traction wheel having a hub, an axle fixed in the hub, a main frame suspended from the axle, an auxiliary frame partly supported on the main frame and partly suspended from the axle, said auxiliary frame being housed within the rim of the traction wheel, and a motor and transmission mechanism supported on the auxiliary frame to drive the 110 traction wheel.

4. In a traction engine, a traction wheel having a hub and a rim connected therewith, said rim extending materially beyond one end of the hub, an axle fixed in the hub, a 120 main frame suspended from the axle, an auxiliary frame housed within the rim of the traction wheel, clamp means connecting one side of the auxiliary frame with the main frame, suspending means connecting 125 the other side of the auxiliary frame with the axle, a motor supported on the auxiliary frame, and means for transmitting motion from the motor to the traction wheel.

5. In a traction engine, a traction wheel 130

having a hub, an axle fixed in the hub, a main frame suspended from the axle, an auxiliary frame suspended from the axle and also connected with the main frame, said auxiliary frame being located within the rim of the traction wheel, a motor supported on the auxiliary frame, means for transmitting motion from the motor to the traction wheel, a steering wheel at the front end of the frame, a seat at the rear end of the frame, and a steering rod guided and supported above the traction wheel, said steering rod including a universal joint.

In testimony whereof I affix my signature.

JULIUS L. ALLEN.
